UNITED STATES PATENT OFFICE

2,634,720

CHIMNEY CONSTRUCTION WITH HEAT
CONTROLLING MINIMIZING MEANS

Robert K. Thulman, Silver Spring, Md.

Application September 18, 1947, Serial No. 774,736

17 Claims. (Cl. 126—307)

1

This invention relates to the art of chimney construction and aims generally to improve the same. It is particularly concerned with minimizing the transfer of heat through the chimney walls when the heating device to which it is attached is operating normally so that a draft may be quickly created and readily sustained.

It is also concerned with a construction for maintaining the temperature on the outside of the chimney construction below the safe limit established for the combustible construction with which it may be in contact, even when the heating device is discharging its products of combustion into the chimney at excessive temperatures caused by overfiring and the like.

Important objects of the invention thus reside in the provision of a new apparatus for dynamically controlling the flow of heat in a chimney construction, and in a chimney construction arranged to embody the same, which method and construction minimize heat loss through the walls of the chimney, quickly attain and maintain with low entering flue gas temperatures a relatively high flue temperature, and automatically discharge excess heat from the chimney in the event of overheating of the furnace or the like.

"Class B" vents and "Class A" chimneys having approval of the Underwriters' Laboratories as heretofore constructed have generally been made up of one-fourth inch thick cement asbestos pipe, laminated pipe including layers of metal and of insulation, tile pipe, and the like. Such chimneys are approved only for installations providing one inch or more of air space clearance around the chimney with respect to any combustible material. However there is no way to assure or adequately check that this clearance requirement of the certificate of approval has been adhered to by the installing contractor and that the expected degree of safety has been obtained. Hence many fires have resulted from such installations, as a result, for example, of overheated furnaces or the like.

These conventional chimneys moreover have a rather high longitudinal temperature gradient and do not heat quickly throughout their height. They thus frequently produce a poor draft when the fire is low and require throwing of much heat up the chimney to create a proper draft with consequent poor efficiency.

Such conventional chimneys moreover adopt expensive constructions where they attempt to increase the traverse temperature gradient to comply, for example, with the Underwriters' Laboratories requirements that chimneys in contact with combustible material have outer wall temperatures, regardless of the stack temperature in the flue, of no more than "ninety degrees Fahrenheit above room temperature"; i. e., no more than one hundred sixty degrees Fahrenheit.

2

Such chimneys, when provided with insulated layers in an effort to meet such requirements, have high inside surface temperatures, particularly in the event of overheating of the furnace. Such high temperatures are apt to be highly detrimental to the flue liners, especially near the point of entrance of the combustion gases.

With these shortcomings of the prior art in mind, the present invention has for further objects, severally and interdependently, the provision of a novel method and arrangement in a chimney construction for maintaining a high transverse temperature gradient through the chimney and a low temperature gradient longitudinally thereof; the provision of a pre-fabricated chimney or the like having air spaces built into it in such a way that no special provisions need be made on the job for the protection of combustibles; the provision of a chimney construction which is heat-retaining at safe flue temperatures and heat-dissipating at flue temperatures which would be excessive in the case of ordinary constructions; and the provision of an arrangement providing a chimney construction which quickly attains an efficient operating temperature throughout its height with small heat loss up the chimney, and which efficiently and safely dissipates excessive heat and avoids overheating in the event of overheating of the furnace.

An additional object of the invention is to provide an arrangement in chimney construction facilitating attic ventilation in a novel manner; and a still further object is to provide a chimney construction capable in itself of obviating condensation difficulties.

In the latter regard, it is known that slow heating of chimneys, and slow cooling thereof, result in condensation near the top of the chimney over extended parts of the heating and cooling cycle. The condensate frequency gravitates to hotter areas and re-evaporates, cyclically. This causes excessive acid attack on the chimney construction, particularly in intermittently-fired installations. The present invention provides a chimney construction of low heat capacity as compared to brick, masonry, and statically insulated constructions. The heating and cooling cycle is thus accelerated with consequent decrease in acid attack on the chimney structures. Indeed, tests with chimneys constructed in accordance with Fig. 1, with entering flue gas temperatures ranging from 400° F. to 1400° F., show that throughout the entire temperature range the construction maintains a flue wall temperature at the top of the chimney higher than that just above the flue gas inlet, with intermediate wall temperatures between these regions, thus keeping the chimney flue surface hotter at its discharge end than at its intake and interme-

diate portions, as is highly desirable in eliminating condensation.

Other objects and advantages of the invention will be apparent from the following detailed description of preferred embodiments of the invention, illustrative of the principles thereof.

With such objects the invention resides in the novel construction by which a thermo-siphon circulation of air is established in channels surrounding the flue so as to increase the temperature gradient through the walls of the chimney construction as its flue temperature increases, and to reduce the temperature gradient lengthwise of the construction, and in the cooperating steps and structural features hereinafter described and claimed.

In the accompanying drawings exemplifying preferred embodiments of the invention:

Fig. 1 is a diagrammatic vertical section through a residential installation embodying one form of the invention.

Fig. 2 is a similar diagrammatic section of a second form thereof.

Fig. 3 is a diagrammatic horizontal section taken on the line 3—3 of Fig. 1.

Fig. 4 is a similar section of a modification.

In the exemplification of Fig. 1 there is shown, schematically, a portion of a small residence comprising a floor 5, a roof 6, and a ceiling 7. Between the floor 5 and the ceiling 7 is a space R of a height sufficient for one or more stories of ordinary rooms, while above the ceiling is an attic space A. Below the floor 5 is a basement B.

The chimney construction embodying the method and arrangement of the present invention includes a flue 8. Surrounding the flue 8 is a first or inner casing 9 having a length slightly less than the height of the flue. The casing 9 is outwardly spaced from the flue 8 to provide an air space 10 between the flue and the casing.

A conventional heater H, which may be of the oil-, gas- or coal-fired type, for example, is shown as resting on the floor F of the basement. The lower end of the flue 8 in the form of Fig. 1 has a horizontally-disposed laterally-extending intake 11 which is connected by means of an elbow 12 to receive the products of combustion from the heater H. In the form shown the lower end of the flue 8 is positioned slightly below the intake 11 and may be provided with any auxiliary device, as exemplified by the drain tube 8a, for example.

The roof 6 is provided with an opening 13 through which the chimney extends. In the present invention a casing or attic ventilating duct 14 is secured within the opening 13 of the roof, extends upwardly, and is spaced outwardly from the casing 9, thus forming a covered chamber communicating with the atmosphere, and which may communicate both with the attic space and the outside atmosphere when attic ventilation is desired. In the form shown the cap or cover 15 is supported above the upper end of the casing 14 in spaced relation thereto so that there may be air communication between the interior of the casing 14 and the outside atmosphere. The cap 15 is apertured to receive the upper end of the flue 8 to which it is connected in sealing relation, and is supported on the structure in any suitable way. For example, it may be supported on and be held centered by legs 14a extending upwardly from the top edge of the casing 14, or otherwise.

In the form shown in Fig. 1 there is, in addition to the first or inner casing 9, a second or outer casing 16 which surrounds the inner casing in

spaced relation thereto. This outer casing 16 may be cylindrical as shown in Fig. 2, rectangular as shown at 16 in Fig. 4, or of any other configuration. At its upper end the casing 16 terminates in proximity to the upper end of the inner casing 9, and preferably in spaced relation therebelow by an amount determined in accordance with the character of the installation. That is to say, if the attic or upper space A is unoccupied then the outer casing 16 terminates somewhere above the floor 7; and if the space A is to be occupied, then the casing preferably terminates above the ceiling of space A, as shown in Fig. 1.

In the form shown the ducts 10 and 18 communicate at their lower ends by way of an enclosed space 17a. The space 17a in this illustrative embodiment is enclosed by the lower end of the outer casing 16 and a closure, floor, or bottom 17 lying between the lower end of the outer casing 16 and the flue 8. The communication may be established from the lower end of the space 18 between the casings to the lower end of the space 10 within the inner casing in any suitable manner. As shown in Fig. 1, for example, the inner casing may be supported so that its lower end terminates a slight distance above the casing bottom or closure 17. Such support may be effected by cutting away the lower edge of the casing 9 to leave supporting feet 9a as shown in Fig. 1, or by any other known or special mode of supporting casing sections. Suitable braces (not shown) may be used to hold the casings in centered relation, when needed. In the form shown in Fig. 1 the upper ends of the casings 9 and 16 terminate below the upper end of the casing 14 so that air may escape from the air space 10 to the atmosphere and air may enter the space 18 between the casings 9 and 16.

As will be appreciated from the following detailed description of the operation of this embodiment, this structural arrangement makes available a new method of controlling transverse flow of heat through the chimney by surrounding the flue with an intussuscepted tubular thermo-siphon air blanket communicating with the atmosphere at its top and the thermo-siphon circulation of which is a function of the differential heating of the inner and outer tubular layers of the blanket by the flue.

Thus, as the heater H is operated, combustion gases enter the flue 8 at its bottom and pass upwardly therethrough. The temperature of the gases entering the flue heats the air in the space 10 within the first surrounding casing 9. This air is therefore caused to flow upwardly transferring heat from the lower portion of the flue 8 to its upper portion. As the air in the space 10 rises, air in the space 18 is drawn downwardly and through the communication in the bottom space 17a, so a countercurrent flow is set up in the spaces 10 and 18. With the arrangement shown in Fig. 1 a part of the air thus circulated passes out under the cap or cover member 15, and part of it may re-circulate downwardly through the duct 18. Air from the attic or other elevated space A may also be drawn downwardly through the duct 13 and pass outwardly under the cap 15.

The flow of air in thermo-siphon circulation through spaces 10 and 18 on initiation of combustion is fairly rapid until the temperature of the air in the space 18 approaches that of the air in the space 10. When this condition arises the thermo-siphon air flow becomes small and

the slowly-moving air layer around the flue 8 within air space 10 maintains the temperature of the flue at such point, from its bottom to its top, that the gas temperature therein is substantially uniform from the bottom to the top of the flue. 5 The re-circulation of air, via the chamber 14, hastens and augments the reduction of thermo-siphon imbalance.

As the temperature of the gases within the flue 8 increases due to overfiring, for example, the 10 temperature of the air within the air space 10 rises. This rise increases the draft through the space 10 and accelerates the air flow upwardly therethrough and downwardly through the space 18. 15 As the air which is drawn into the space 18 is cooler than that issuing from space 10, and as its rate of induction is increased by a rise in the flue temperature, the arrangement tends actually to reduce the temperature in the air space 18 in the event of overheating of the furnace.

As long as the temperature within flue 8 is within the normal operating limits of, say three hundred to four hundred degrees Fahrenheit for an oil-burning installation, or three hundred to eight hundred degrees Fahrenheit, depending on the condition of the fire, in the case of a coal-burning installation, the flow of air through the spaces 18 and 10 stabilizes at a relatively slow rate, so that the temperature of the flue 8 is kept substantially even throughout its height; i. e., the longitudinal temperature gradient of the flue becomes very small. Such maintenance of temperature is sufficient to maintain the necessary operating draft at the heater for economical and satisfactory heating purposes without excessive loss of heat up the stack.

As mentioned, when the temperature within the flue rises, the temperature of the air within the space 10 is increased thus augmenting the draft through the space 10 and the eduction of air into the space 18. The increase of air flow downwardly through the space 18 cools the surface of the casing 9 and prevents any excessive rise in temperature of the casing 16. Because of this mode of operation the chimney may with safety be erected with the casing 16 positioned directly against inflammable material, as the wooden construction elements 19, 20, 21, 22, 23, 24, 5 and 7, for example, such arrangements being exemplified in Figs. 1, 3 and 4. Because the heating of the descending air in the casing 18 opposes the thermo-siphon circulation, control of this heating, as by re-circulation, or control of the heat passing through the wall 9, may be adjusted to concur the minimum rate of air circulation with the normal stack temperature range desired in the installation.

Demonstration and actual testing have satisfactorily proven that with the method and construction exemplified in Fig. 1 heat loss through the walls of the chimney is slight and that substantially uniform temperature throughout the flue has been maintained.

The embodiment illustrated in Fig. 1 is considered particularly well adapted for maintenance of uniform stack temperatures, and satisfactory for preventing undue rise in temperature of the casing 16 in the event of overheating of the furnace. It is also well adapted for attic ventilation and draws a substantial part of the thermo-siphon circulated air from the attic space since the hotter air, particularly in the case of large temperature differentials, tends to stratify thereabove and escape under the cap 15. 70

Attic ventilation is particularly desirable during summer weather for cooling of the attic space, and during winter for prevention of condensation therein. With the preferred arrangement of this invention, when the furnace is shut down, as during summer weather, attic ventilation continues in an uninterrupted manner through the ventilating duct 14 and the communication with the atmosphere under the cap 15. With normal winter operation of the furnace (or with the so-called "summer-winter hook-up" for year round heating of water) a substantial quantity of air, say fifty to one hundred cubic feet per minute, may circulate through the ducts 18 and 10 and a substantial proportion of this air may be pulled from the attic space and delivered to the outside atmosphere.

The heights of the casings forming the air ducts 10 and 18, and the character of flow of air between the casings 18 and 9 may be determined by calculation in accordance with any particular construction. The effective lengths of the inner and outer air ducts, defining the spaces 10 and 18, are preferably balanced so that under normal stack temperatures air flow is very small, for example, of the order of one cubic foot per second, or less. The testing above mentioned has established that the outside temperature of the outer casing 16 is considerably below the ignition points of wood normally used for low cost construction of houses and the like. One series of tests showed the temperature of the outer casing to be 90° Fahrenheit with flue temperature of 800° Fahrenheit when simple sheet metal casings were employed. The construction of the present invention thus maintains the temperature of the outer casing well below the 160° Fahrenheit limit set by the Underwriters' requirements.

40 Freedom of communication between the lower ends of the duct spaces 18 and 10 and the resistance to air flow through the ducts has a direct influence on the circulation of air in the construction. Thus by adjusting this resistance, as by raising or lowering the lower end of the tube 9 or varying the height of the legs 9a thereunder, or by providing the communicating passage with a valve such as the sleeve valve shown in Fig. 2, for example, a satisfactory adjustment of flow resistance and air flow may be obtained.

45 As relatively cool air is continuously circulated against the lower end of the flue 8 which receives the hot products of combustion, excessive heating of the flue liner is avoided with consequent increase in its life. The flue or liner 8 may consist of stovepipe sheet, steel, coated with vitreous enamel, asbestos cement tubing, stovepipe tile or any other material suitable to withstand the contemplated flue temperature. The inner duct 9 may be formed of any suitable material and is preferably formed of aluminum tubing to take advantage of its reflective value in reducing transfer of heat through the chimney structure. This provision reduces heat transfer to the outer duct 18 and reduces the flow-retarding effect thereof. When it is desired to effect more of such retardation, for example in certain cases in which the outer duct terminates at attic floor level while the inner duct extends to roof height, so that there is a wide difference in length of the two heated columns, the dividing wall between them may be of black iron or other form relatively efficient in heat transfer. The outer duct 16 may be formed of any suitable material such as galvanized iron or the like,

or advantageously may be formed of bright material such as aluminum still further to reduce by its reflective value the outer wall temperature of the construction, and retain in the outer duct 18 the heat transferred thereto through the wall 9.

The relative proportions of the flue, inner casing, and outer casing may be varied within wide limits so long as the free circulation of air through the spaces 18 and 10 required by the new method is provided for. For example, the three flues may be of galvanized stovepipe six, eight and ten inches in diameter, respectively, mutually spaced in any suitable manner, as by spacers, indentation of the casing walls, or otherwise.

As above indicated the invention may be embodied in other arrangements than those described herein to exemplify its principles. In the embodiment shown in Figs. 2 and 4, for example, the flue 8' is surrounded by an inner casing 9' and an outer casing 16', and the communication between the passages 18' and 10' is regulated by a sleeve valve 25' controllable by a knob 26' which is movable in a slot 27' in the casing wall 17'. In this form the flue 8' exits through the bottom of the casing. In addition the air passing upwardly from duct 10' is discharged to atmosphere above a partition 28' underlying the cap or cover 15', and the outer casing 16' is provided with an adjustable extension 29' for regulating the proportion of attic air and outside air drawn into the space 18'. With this arrangement and a relatively tight attic space any overheating of the furnace causes the induction of a considerable volume of cool outdoor air into the duct 18' and further guards against excessive rise of temperature of the outer casing 16'. When the valve 25' is provided the slot 27' is preferably so formed that complete closing of the valve 25' is prevented so that some thermo-syphon circulation is insured at all times.

Preferred forms of the method and apparatus of the invention have been described herein more or less precisely as to details. It is to be understood, however, that the invention is not to be considered as limited thereby, that changes may be made in the arrangement and proportions of parts, and that equivalents may be substituted without departing from the spirit and scope of the invention.

I claim as my invention:

1. A chimney construction for thermo-syphon balanced draft comprising a flue, a plurality of thermo-syphon air flow ducts surrounding said flue and outwardly spaced from it and from each other, said ducts having substantially equal effective lengths and having air flow communication at their lower ends to provide for inducing of countercurrent air flow therein by heat transmitted laterally from said flue for increasing the transverse temperature gradient and decreasing the longitudinal temperature gradient of said chimney, said flue discharging to the atmosphere at its upper end and said thermo-syphon ducts each communicating with the atmosphere at its upper end ahead of and separately from the discharge of the flue thereto so that circulation in said ducts is not affected by the draft in said flue.

2. A chimney construction for thermo-syphon balanced draft comprising a flue, a plurality of thermo-syphon air flow ducts surrounding said flue and outwardly spaced from it and from each other, said ducts having substantially equal effective lengths and having air flow communication

70
75

at their lower ends to provide for inducing of countercurrent air flow therein by heat transmitted laterally from said flue for increasing the transverse temperature gradient and decreasing the longitudinal temperature gradient of said chimney, said flue discharging to the atmosphere at its upper end and said thermo-syphon ducts each communicating with the atmosphere at its upper end ahead of and separately from the discharge of the flue thereto so that circulation in said ducts is not affected by the draft in said flue, the relative heights of said ducts being adjusted to regulate the thermo-syphon induction of draft therein by the heat transmitted laterally from

15 said flue.

3. A chimney construction for thermo-syphon balanced draft comprising a flue, a plurality of thermo-syphon air flow ducts surrounding said flue and outwardly spaced from it and from each other, said ducts having substantially equal effective lengths and having air flow communication at their lower ends to provide for inducing of countercurrent air flow therein by heat transmitted laterally from said flue for increasing the transverse temperature gradient and decreasing the longitudinal temperature gradient of said chimney, said flue discharging to the atmosphere at its upper end and said thermo-syphon ducts each communicating with the atmosphere at its upper end ahead of and separately from the discharge of the flue thereto so that circulation in said ducts is not affected by the draft in said flue, the relative heights of said ducts being adjusted to regulate the thermo-syphon induction of draft therein by the heat transmitted laterally from

20
25
30
35

4. A chimney construction for thermo-syphon balanced draft comprising a flue, a plurality of thermo-syphon air flow ducts surrounding said flue and outwardly spaced from it and from each other, said ducts having substantially equal effective lengths and having air flow communication at their lower ends to provide for inducing of countercurrent air flow therein by heat transmitted laterally from said flue for increasing the transverse temperature gradient and decreasing the longitudinal temperature gradient of said chimney, said flue discharging to the atmosphere at its upper end and said thermo-syphon ducts each communicating with the atmosphere at its upper end ahead of and separately from the discharge of the flue thereto so that circulation in said ducts is not affected by the draft in said flue, the relative heights of said ducts and the degree of flow communication therebetween being adjusted to regulate the thermo-syphon induction of draft therein by the heat transmitted laterally from

40
45
50
55
60
65

5. A chimney construction for connection to a furnace comprising a chimney flue, means positioned about said flue for confining upflowing air in heat exchange relation to said flue, means for confining downflowing air in heat exchange relation to and extending substantially throughout the length of said upflow air confining means, means for admitting air to the upper end of said downflow confining means and for delivering air freely from the upper end of said upflow confining means, said means for confining upflowing air delivering the air to the atmosphere ahead of and independently of the flue and means establishing communication between the lower ends of said downflow and upflow confining means whereby downflow and upflow columns of substantially equal height are provided through which thermo-

syphon flow of air occurs dependent on the differential heat transfer between the flue and the two otherwise substantially balanced columns and unaffected by draft in the flue.

6. A chimney construction according to claim 5 further comprising an air chamber positioned about the upper end of said air flow confining means, the downflow air confining means communicating with said air chamber and said air chamber provided with an opening in its lower portion for communicating with an attic space.

7. A chimney construction according to claim 5 further comprising an air chamber arranged adjacent the upper ends of said air-flow confining means and receiving warmed air from said upflow means and delivering air to said downflow confining means, said air chamber further communicating with the surrounding atmosphere.

8. A chimney construction according to claim 7 in which said air chamber communicates both with the outer atmosphere and further provided with an opening in its lower portion for communication with an adjacent attic space.

9. A chimney construction comprising a central flue, an inner metallic duct element nearly as long as the flue and surrounding and spaced therefrom throughout its height to define therewith an annular air upflow passage, an outer duct element surrounding and spaced from said inner metallic duct element throughout at least a major portion of its length to define therewith an annular air downflow passage, said downflow and upflow passages communicating at their bottoms and being otherwise closed except at their upper ends, a chimney box surrounding the upper ends of said duct elements and flue and spaced therefrom, said chimney box having a top and communicating with the atmosphere below its top and independently of the flue, whereby heating of the flue produces thermo-syphon circulation of air through said downflow and upflow passage controlled by the transmission of heat from said flue to said upflow passage and by conduction through said metallic duct to said downflow passage.

10. A chimney construction according to claim 9, in which said chimney box is further provided with an opening in its lower portion for communication with an attic space.

11. A chimney construction comprising a central heat conductive flue for flue gases, an air circulating system in which air-flow is accelerated solely by differential thermo-syphon action arranged in surrounding relation to said flue; said air circulating system comprising a heat conductive inner duct surrounding said flue throughout the greater part of its length in spaced relation thereto, said inner duct and flue defining an air upflow space therebetween, said air circulating system further comprising an outer duct surrounding said inner duct and spaced therefrom, said ducts defining an air downflow space therebetween, said air circulating means also comprising bottom closure means surrounding said flue and extending to said outer duct and closing the space therebetween, and said inner duct having an open portion at its end adjacent said closure means establishing communication between said outer and inner air-flow spaces, the upper end of said air downflow space being in communication with the atmosphere, and the upper end of the air upflow space discharging to the atmosphere ahead of said flue at a location out of direct communication with said flue and at which the pressure is not reduced by the flue draft, so that the

flue draft does not accelerate flow of air through said ducts; whereby heating of the flue causing heating of the air in said air upflow space constitutes the sole means acting to promote thermo-syphon circulation of air through said downflow and upflow spaces, while transfer of heat to said heat conductive inner duct in turn causing heating of the air in said air downflow space constitutes means acting to retard such thermo-syphon circulation, the net result of such differential heating therefor being that on substantial rise in temperature of the flue gases supplied to said central flue the lag in heating of said heat conductive inner duct produces a time delay between the circulation promoting and retarding actions so that the thermo-syphon circulation is first speeded up as the central flue heats and then slows down as the inner duct becomes heated and stabilizes at a rate determined by the differential heating; the dependence of air-circulation on the thermo-syphon effect of heating of the air in the upflow space contributing to rapid heating of the upper part of the flue when hot flue gases are first supplied to the flue and thus reducing condensation in the upper part of the flue and promoting draft therein.

12. A chimney construction according to claim 11, in which the open portion of the inner duct adjacent the bottom closure constituting a restriction to further control the rate of thermo-syphon circulation.

13. A chimney construction according to claim 11, further comprising hood means surrounding the upper end of the central flue and extending outwardly over, but in spaced relation to, the upper open ends of both the inner and outer ducts.

14. A chimney construction according to claim 13, further comprising a chimney box surrounding said ducts and having an upper edge portion terminating in spaced relation to said hood means, from which box the outer duct draws its supply of air and into which box the inner duct discharges the warmed air.

15. A chimney construction according to claim 14, in which said chimney box is further provided with an opening in its lower portion for communicating with an attic space.

16. A chimney construction according to claim 11, further comprising a covered chimney box surrounding the upper ends of the inner and outer air ducts, from which the downflowing air is drawn and into which the upflowing air is discharged, said chimney box having an opening near the top thereof communicating with the surrounding atmosphere, and providing for partial recirculating of the circulated air.

17. A chimney construction according to claim 16, in which said chimney box is further provided with an opening in its lower portion for communicating with an attic space.
